Primary Examiner — Marie D. Fast Horse(57) **CLAIM**

The ornamental design for an external hard disk driver, as shown and described.

DESCRIPTION

FIG. 1 is a rear, left, and bottom perspective view of an external hard disk driver showing our new design; FIG. 2 is a front, right, and bottom perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; FIG. 9 is an enlarged view of portion 9 shown in FIG. 1; and, FIG. 10 a rear, left, and top perspective view thereof, shown in an alternate configuration.

The dash-dash broken lines in the drawings depict portions of the external hard disk driver that form no part of the claimed design. The dot-dash broken lines represent boundaries of the enlarged portion shown in FIGS. 1 and 9 that form no part of the claimed design.
